UNITED STATES PATENT OFFICE.

GUY R. SWENSON, OF ROCKFORD, ILLINOIS.

DIMMER CAP FOR HEADLIGHT BULBS.

Application filed January 2, 1925. Serial No. 34.

This invention relates in general to head-lights for motor vehicles and has more particular reference to means for dimming the headlight's by deflecting certain rays emanating from the incandescent light bulbs.

The primary purpose of my invention is to provide an improved dimmer cap adapted to be attached to the bulb of a headlight having a parabolic reflector, the cap being preferably but not necessarily made of sheet metal and comprising a one-piece body having a lower part adapted to intercept rays which would normally strike the bottom portion of the reflector and be reflected forwardly into the eyes of an approaching driver, and an upper part adapted to intercept the rays which would normally be directed forwardly and upwardly and produce a direct glare which is harmful to the approaching driver, said body being cut away in front of said lower part and beneath said upper part to allow unrestricted passage of the rays forwardly and downwardly to illuminate the road bed in front of the car and being further cut away above said lower part and at the rear of said upper part to allow unrestricted passage of the rays upwardly to strike the upper portion of the reflector and be thereby reflected forwardly and downwardly to illuminate the road bed farther ahead.

Another purpose of my invention is to provide a dimmer cap of the character described shaped to conform to and closely fit on a bulb and having arms adapted to embrace the bulb and to interlock so as to hold the cap from displacement. Another purpose is to provide the cap with a retaining lug adapted to enter the bayonet opening of the light socket to hold the dimmer cap from rotative displacement.

Still another purpose is to provide a dimmer cap embodying the features mentioned so constructed that it may be produced at a comparatively low cost.

Referring to the drawing:

Figure 1, is a diagrammatic vertical section through a parabolic reflector showing in operative relation thereto a dimmer cap embodying my invention;

Fig. 2, is an enlarged vertical section through the dimmer cap, showing its operative relation to the bulb and socket;

Fig. 3, is a top view of the dimmer cap;

Fig. 4, is an end view looking at the rear or attaching end;

Fig. 5, is a side view of the cap;

Fig. 6, is a front view thereof; and

Fig. 7, is a detail view of the interlocking attaching arms.

In illustrating my invention only the reflector 8 of a headlight is shown, the reflector being of the usual parabolic form. The incandescent light bulb 9 and socket 11 having a bayonet slot 12 for holding the bulb in position are likewise of conventional form.

My invention contemplates the provision of a dimmer cap formed of a single piece of material, preferably of sheet metal which may be easily bent into shape and pressed or formed by stamping operations into the desired form, thus promoting economy in the cost of production. My invention further contemplates shaping the body of the dimmer cap in a particularly novel and advantageous manner to intercept certain rays emanating from the bulb and allow unrestricted passage of other rays so that they will function to advantage. Furthermore, I propose to so shape the body piece as to include attaching elements and means for preventing displacement of the body in any direction.

The one-piece sheet metal body is substantially spherical in form but is so cut away at its top and at one end as to fit over a bulb from beneath. The body, designated generally by 13, has a pair of attaching arms 14 and 15 adapted to embrace the neck portion of the bulb and to be interlocked one with the other for holding the cap in position. The interlocking means at present employed comprises an eye 16 in the arm 14 adapted to receive the reduced finger 17 on the arm 15 and to be turned back to a holding position as clearly shown in Figs. 3 and 4. The body is held from rotative displacement on the bulb by a retaining lug 18 adapted to enter the bayonet slot 12.

The body has two major light intercepting portions which will for purpose of clarity be referred to as the lower and upper body parts 19 and 21 respectively. The body part 21 is located almost wholly in front of the body part 19. The body is cut away to provide certain areas or zones through which the light rays emanating

from the bulb may pass unrestricted. One of these cut-aways is in front of the lower part 19 and beneath the upper part 21 to allow unrestricted passage of the light rays 5 for directly illuminating the road bed close to the car; and the other, located above the lower part and at the rear of the upper part allows unrestricted passage of the rays to the upper portion of the reflector so that 10 they will be reflected forwardly and downwardly for illuminating the road bed farther ahead of the car than those rays emanating from the first-mentioned opening. It will be manifest that the opaque lower 15 body part 19 prevents the rays from striking the lower portion of the reflector and consequently from being reflected forwardly and upwardly so as to be dangerous to an approaching driver, also that the opaque body portion 21 intercepts light rays which 20 would normally be directed forwardly and upwardly and consequently objectionable.

It will be manifest from the foregoing 25 that the dimmer cap may be easily attached or removed as the case may require; that when in position it is effectually held from displacement; that the several parts of the body are in permanent operative relation and that they will serve in a practical and 30 satisfactory manner the purposes intended; and that the construction is such as will permit its production at a comparatively low cost.

It is believed that the foregoing conveys 35 a clear understanding of my invention and while I have illustrated and described but a single working embodiment it should be understood that changes might be made in details of construction without departing 40 from the spirit and scope of the invention as expressed in the appended claims, in which—

I claim:

1. A dimmer cap for the incandescent

bulb in a headlight having a parabolic reflector, comprising a one-piece sheet material body shaped to conform to and closely fit on a bulb and providing a lower part adapted to intercept rays which would normally strike the bottom portion of the reflector and an upper part located forwardly of the lower part and adapted to intercept rays which would normally be directed forwardly and upwardly, said upper and lower parts being joined by an integral connecting web, said body being cut away in front of said lower part and beneath said upper part to allow unrestricted passage of the rays forwardly and downwardly and being further cut away above said lower part and at the rear of said upper part to allow unrestricted passage of the rays upwardly to strike the upper portion of the reflector, the upper edges of said lower part and the lower edges of said upper part being substantially in the same horizontal plane. 45 50 55 60 65

2. A dimmer cap as set forth in claim 1 having a pair of arms integral with said lower part and adapted to embrace the stem end of the bulb on the upper portion thereof and having means at the free ends thereof for connecting the arms together to hold the cap thereon, said connecting means permitting of the connection of said arms despite slight variations in the diameter of the 70 75 stem end of the bulb.

3. A dimmer cap as set forth in claim 1 having a retaining lug adapted to enter the bayonet opening in the socket to prevent rotative displacement of the cap. 80

4. The combination with a headlight reflector and a light bulb therefor having a socket provided with bayonet slots, of a dimmer fitting about the bulb and having a positioning lug to engage in a bayonet slot 85 for the purpose described.

GUY R. SWENSON.
